ELECTRIC BLANKET CONTROL BOX OR SIMILAR ARTICLE

Monte L. Levin, Roslyn Heights, N.Y., assignor to Field-
crest Mills, Inc., a corporation of Delaware

Application July 3, 1958, Serial No. 51,638

Term of patent 14 years

(Cl. D26—13)

Figure 1 is a perspective view of an electric blanket control box or similar article, showing my new design with the cover opened;

Figure 2 is a top plan view, with the cover closed;

Figure 3 is a front elevational view, the rear being substantially a mirror image thereof; and

Figure 4 is an end elevational view, the opposite end being substantially a mirror image thereof.

The dominant features of my new design are shown in solid lines in the drawing.

I claim:

The ornamental design for an electric blanket control box or similar article, as shown and described.
